[57] CLAIM

The ornamental design for a loudspeaker, as shown and described.

DESCRIPTION

FIG. 1 is a rear perspective view of a loudspeaker showing my new design;

FIG. 2 is a rear elevational view thereof;

FIG. 3 is a side elevational view thereof, the opposite side being a mirror image;

FIG. 4 is a front elevational view thereof;

FIG. 5 is a rear perspective view of a second embodiment of the loudspeaker of FIG. 1;

FIG. 6 is a rear elevational view of the embodiment of FIG. 5; and

FIG. 7 is a side elevational view of the embodiment of FIG. 5, the opposite side being a mirror image.

The front elevation of the second embodiment illustrated in FIG. 5 is identical to that shown in FIG. 4.

FIG. 4

FIG. 5

FIG. 6
